UNITED STATES PATENT OFFICE.

SIDNEY BLUMENTHAL, OF NEW YORK, N. Y., ASSIGNOR TO SIDNEY BLUMENTHAL & COMPANY, INCORPORATED, OF NEW YORK, N. Y., A CORPORATION OF NEW YORK.

DESIGN FOR VELVET.

46,466.

Specification for Design.

Patented Sept. 29, 1914.

Application filed April 10, 1913. Serial No. 760 321. Term of patent 7 years.

To all whom it may concern:

Be it known that I, SIDNEY BLUMENTHAL, a citizen of the United States, and resident of the borough of Manhattan, in the city and State of New York, have invented a new, original, and ornamental Design for Velvet, of which the following is a specification, reference being had to the accompanying drawing, forming part thereof.

The figure is a plan view of a portion of a piece of velvet illustrating my new design.

I claim:

The ornamental design for velvet, as shown.

SIDNEY BLUMENTHAL.

Witnesses:

F. GEORGE BARRY,
C. S. SUNDGREN.
